M. R. PAVON.
FUEL OIL FURNACE BURNER.
APPLICATION FILED JULY 11, 1918.

Patented Mar. 18, 1919.

Manuel Rocha Pavon,
By Lincoln Horntag.
Attorney

UNITED STATES PATENT OFFICE.

MANUEL ROCHA PAVON, OF OAKLAND, CALIFORNIA.

FUEL-OIL-FURNACE BURNER.

1,297,589.

Specification of Letters Patent. Patented Mar. 18, 1919.

Application filed July 11, 1918. Serial No. 244,391.

To all whom it may concern:

Be it known that I, MANUEL ROCHA PAVON, a citizen of the United States, residing at the city of Oakland, in the county of Alameda and State of California, the undersigned, have invented certain new and useful Improvements in Fuel-Oil-Furnace Burners, of which the following is a specification.

My invention relates to improvements in fuel oil furnace burners. Although my improved burner is particularly adapted to the use of crude oil or common fuel oil other oils for burning may be used with good results. The object of my invention is the production of a device capable of the production of an intensely hot flame in the minimum time, especially saving time and labor as well as fuel, the oil consumed producing the maximum amount of heat units due to the process of atomizing, gasifying and superheating accomplished by its use, resulting in a highly combustible gas for the operation.

In the figure a tube A is held in a sleeve J wherein it is secured. A branch B has two rear openings and one front opening, each of said openings being threaded to engage parts to be held therein. One of the rear openings of said branch B is level, wherein the sleeve J holding the tube A is secured. The other rear opening of said branch B is inclined and is threaded for the reception of an appropriate feeding pipe or connection. A connecting tube C has one end secured in the front opening of said branch B and is held circumferentially by the union or joint L. The joint L is screwed in the rear opening of cylindrical casing or tube M and the forward opening of tube C holds a tube which is screwed therein and marked D. The tube D extends from the tube C through the union L in the casing M and its front end penetrates the rear end of the inner tube F which is secured in the casing M. The front end of the inner tube F passes through and extends beyond the front end of outer tube or casing M. The outer tube or casing M is provided with ports H opening into the channel formed between said outer tube and the inner tube F, said tubes being spaced apart for the greater part of their length. The said channel continues into tube F by reason of the fact that the front end of tube D penetrating inner tube F is spaced from said inner tube so as to form a channel between

the said tubes. The forward ends of tubes A and D are tapered so as to facilitate the passage of the oil, steam or air contacting therewith. The burner may be supported in the furnace by attachment to branch B and by way of tube A.

In the operation fuel oil is injected through the inclined passage of branch B while steam or compressed air is forced through tube A and meets the entering oil forwardly, whence mixing they pass through tube C and thence the resulting vapor blows through tube D of smaller caliber for compression as shown and forming a partial vacuum in space E such vacuum draws heated air through ports H by way of the channel between tubes M and F leading into said tube F, wherein such heated air mixing with the vapor gasifies it and thus produces a gas of highly combustible nature igniting at opening G.

Tubes A, C, D and F are substantially longitudinally and centrally in alinement.

In the construction of said burner I have found that no machinery is required except a pipe cutter and a pipe threader and no material other than standard wrought iron or steel pipe and fittings of suitable sizes depending on the size of the burner. I consider it possible to construct a burner of cast iron or cast steel and of extremely large sizes. I believe this material would make a better looking device, although more expensive, for such sizes.

I claim:

1. An oil burner having a rear member with twin passages therein converging forwardly to a single passage, hollow members extending forwardly from said rear member, a shell gripping one of said hollow members and having an extension therefrom forming a tube having an opening therein, and an inner tube secured in said tube and spaced therefrom so as to form a channel leading from said opening rearwardly to the rear end of said inner tube, the said inner tube containing the front end of the front member of said hollow members and the caliber of said inner tube being greater than the exterior of said front member so as to form a channel between the same continuing from the channel first mentioned.

2. An oil burner having a plurality of rear passages converging forwardly to a single passage, tubing extending forwardly from

the point of convergence of said passages, a barrel extending forwardly from said tubing and having a front opening, a tube in said barrel but out of contact therewith rearwardly from said front opening whereby a channel is formed open to said opening, the rear end of said tube being centrally penetrated by said tubing for delivering a mixture therein and forming a channel between 5 said tubing and said barrel and the rear end of said tube being spaced from the rear end of said barrel to form a chamber between the same.

3. An oil burner having a plurality of 15 rear passages converging forwardly to a single passage, one of said passages being penetrated therethrough by a pipe engaging the wall thereof and the other of said passages being partly formed by said wall, tubing 20 extending forwardly from the point of convergence of the passages as formed, a barrel extending forwardly from said tubing and having front side apertures, a tube in said barrel but out of contact therewith 25 rearwardly from said apertures whereby a channel is formed open to said apertures, the rear end of said tube being centrally penetrated by said tubing for delivering a mixture therein and forming a channel between said tubing and said barrel and said tube projecting beyond the front end of said barrel.

ture therein and forming a channel between 30 said tubing and said barrel.

4. An oil burner having a plurality of rear passages converging forwardly to a single passage, one of said passages being penetrated therethrough by a pipe engaging the wall thereof and the other of said 35 passages being inclined on one side thereof and on its other side being partly formed by said wall and the wall of said pipe, connected tubing extending forwardly from the point of convergence of the passages as formed, a 40 barrel extending forwardly from said tubing and having front side apertures, a tube in said barrel but out of contact therewith rearwardly from said apertures whereby a channel is formed open to said apertures, the rear 45 end of said tube being centrally penetrated by said tubing for delivering a mixture therein and forming a channel between said tubing and said barrel and said tube projecting beyond the front end of said barrel.

In testimony whereof I affix my signature, 50 in presence of two witnesses.

MANUEL ROCHA PAVON.
